UNITED STATES PATENT OFFICE.

WALTER PRINGLE AND ROBERT PRINGLE, OF HAWICK, SCOTLAND.

THREAD-CARRIER FOR KNITTING-MACHINES.

SPECIFICATION forming part of Letters Patent No. 507,929, dated October 31, 1893.

Application filed August 11, 1893. Serial No. 482,886. (No model.) Patented in England May 7, 1892, No. 8,674.

To all whom it may concern:

Be it known that we, WALTER PRINGLE and ROBERT PRINGLE, subjects of the Queen of Great Britain, residing at Hawick, in the county of Roxburgh, Scotland, have invented certain new and useful Improvements in Thread-Carriers for Knitting-Machines, (for which we have obtained Letters Patent in Great Britain, No. 8,674, dated May 7, 1892;) and we do hereby declare the following to be a full, clear, and exact description of the invention, such as will enable others skilled in the art to which it appertains to make and use the same.

Our invention relates to thread carriers or guides for straight bar knitting machines with movable needles, and the object of our improvements is the manufacture of a better class of knitted plaited goods or fabrics than it is possible to make with any other appliance with which we are acquainted.

We attain the object of our invention by the mechanism illustrated in the accompanying drawings in which—

Figure 1 is a side elevation of our improved thread carrier; Fig. 2 a front elevation of the same and Fig. 3 a plan of the same. Fig. 4 is a side elevation of an alternative method of constructing our thread carrier; Fig. 5 an elevation of the arrangement of cams used for making an article which is fashioned at the sides only and Fig. 6 an elevation of the arrangement of the cams used for making the heel and instep of a stocking.

Our improved carrier is attached to a carrier rod *a* which may be of any of the ordinary sections, and mounted and actuated by the usual mechanisms, the length of the traverse of the same being regulated by stops which are moved by screws as is usual in this class of machines. The carrier rod *a* is provided with brackets *b* to which the plate *c* is adjustably attached, this latter carrying the thread guide *d* which in our improved carrier is made with an eye *e* for the knitting thread, and a tube *f* for the plaiting thread. This tube *f* is fitted to slide in the end of the guide *d* and is connected by a link *g* to a lever *h* which is pivoted at *k* upon the plate *c* and is acted upon by a spring *l* which always tends to keep the tube *f* in its lowest position.

In the arrangement shown in Fig. 4 the tube *f* is connected directly to the lever *h*, the end of which is slotted to allow of its moving freely, while the upper end of the tube is guided by the plate *c*.

In the manufacture of knitted plaited work it is desirable that the plaiting thread should be laid upon the needles in such a position that when the loops are knocked over the same the plaiting thread shall appear upon the face of the fabric, and we do this with our carrier.

When making an article which has to be fashioned at the sides only we use to each division of the machine the arrangement of cams shown at Fig. 5. The cams *m* at the left hand side of each division are all mounted upon a rod *n* which is connected at the end of the machine to the fashioning screw nut, by which the cams are maintained at the same relative position with the selvage of the fabric. The cams *o* at the right hand side of each division of needles are mounted upon a rod *p*, which is connected to, and actuated by a screw nut at the end of the machine opposite to that carrying the screw for the rod *n*. When the thread carriers start to traverse across the needles from left to right, the levers *h* pass from under the cams *m* whereupon the springs *l* force down the tubes *f* which remain in their lowest position until the carriers reach the opposite side of the fabric, when the levers *h* pass under the cams *o*, which raise the tubes *f* and allow the sinkers to come forward and divide the thread upon the needles without damaging the carriers or sinkers.

When a knitted plaited stocking is being made with our carriers, the leg portion is made in the same way as an article fashioned at the sides only. When the heel and instep are reached, the stocking is divided, and two additional heelng thread carriers brought into action, the legging being then used for the instep. The heel pieces require fashioning at the outside edges and the cams *q* and *r* Fig. 6 are used, these cams being mounted upon rods *s* and *t* which are connected to and actuated by the fashioning screws. The inside edges of the heel and outside edges of the instep are made parallel to each other, and

- the tubes of the thread carriers when at these edges are raised by the cams *u* and *v* which may be arranged to act upon the instep and heel carriers alternately. The cams *u* and *v* may be removably attached to a fixed rod *w* or each cam may be attached to a separate rod capable of being moved endwise clear of the carriers when required. After the heel is completed the heel carriers and the cams *u* and *v* are thrown out of action, and the foot and toe of the stocking made by the legging carrier, the cams *q* and *r* being brought into action for this portion of the stocking and for the fashionings at the toe.
- 15 We are aware that knitting machine thread carriers have been made with one fixed eye, and with an eye capable of being moved to the right or left of the former, and we lay no claim to carriers of this description, nor to

the general principle of a thread carrier with two guide eyes.

What we do claim, and desire to secure by Letters Patent in the United States, is—

A knitting machine thread carrier having one fixed eye for the knitting thread, and a second eye in the form of a tube for the plaiting thread, the tube being connected to a lever by which it can be raised and lowered at the end and beginning of the traverse of the thread carrier by means of cam surfaces mounted upon bars capable of being moved in and out.

WALTER PRINGLE.
ROBERT PRINGLE.
